UNITED STATES PATENT OFFICE.

HENRY H. THORP, OF CLEVELAND, OHIO, ASSIGNOR TO THE H. H. THOR MANUFACTURING COMPANY, OF SAME PLACE.

DESIGN FOR A FONT OF PRINTING-TYPE.

SPECIFICATION forming part of Design No. 12,975, dated June 13, 1882.

Application filed April 24, 1882. Term of patent 14 years.

To all whom it may concern:

Be it known that I, HENRY H. THORP, of the city of Cleveland, in the county of Cuyahoga and State of Ohio, have produced a new and original Design for Printing-Types, of which the accompanying specimen or impression is an exact representation, and is made a part of this specification.

What I claim as my invention, and desire to secure by Letters Patent, is—

The design herein set forth for font of printing-types.

Cleveland, Ohio, April 19, 1882.

HENRY H. THORP.
